WELL SWAB

Charles S. Crickmer, Dallas, Tex.

Application March 3, 1941, Serial No. 381,505

7 Claims. (Cl. 309—33)

This invention relates to new and useful improvements in well swabs.

The usual type of well swab ordinarily includes a plurality of individual and separate parts, such as the mandrel, supporting thimble, swab cup and valve, which parts are assembled to provide a complete device. Any one or all of these parts, and particularly the swab cup are subject to wear and therefore, require replacement. In order to replace any of the worn parts, the device must be completely dis-assembled which requires time and in many instances, considerable labor in the event the connections stick and become difficult to detach. Further, the device, with the exception of the resilient swab cup, is intended to be permanent and for this reason, the original cost, as well as the replacement expense, is relatively high.

It is, therefore, one object of this invention to provide an improved well swab which is so simple and inexpensive in manufacture that the swab cup and mandrel may be discarded when the cup becomes worn, whereby replacement of worn parts is unnecessary.

An important object of the invention is to provide an improved well swab, wherein the swab cup is vulcanized, or otherwise permanently fastened to a tubular support, whereby the use of a separate retaining thimble for the swab cup is unnecessary; the construction being such that the tubular support may be coupled to a check valve, whereby the valve is not an integral part of the swab assembly, with the result that said swab includes a minimum number of parts which reduces the cost of manufacture to the point where the entire swab assembly may be economically discarded when worn and replaced with a new assembly.

A particular object of the invention is to provide an improved swab of the character described, wherein the bore of the swab cup is permanently fastened to the tubular support, the upper portion of the cup being spaced from the support to form an annular sealing lip which is adapted to be expanded by fluid when the assembly is lifted upwardly through the well pipe.

Still another object of the invention is to provide a swab cup having its lower portion suitably reinforced either by an auxiliary reinforcing element or by hardening the material at the lower end of the cup, together with means for limiting the radial movement of the sealing lip at the upper portion of the cup.

A still further object of the invention is to provide an improved device, of the character de-

scribed, wherein the flexible swab cup may be permanently fastened to the mandrel by welding or otherwise securing the metallic reinforcing thimble which encloses the cup to the mandrel, whereby the cup is permanently mounted on the mandrel without the necessity of actually bonding the cup proper to the mandrel.

The construction designed to carry out the invention will be hereinafter described together with other features of the invention.

The invention will be more readily understood from a reading of the following specification and by reference to the accompanying drawing, as an example of the invention is shown, and wherein:

Figure 1 is a view, partly in section and partly in elevation of a well swab, constructed in accordance with the invention, and illustrating the same within a well tubing,

20 Figure 2 is a horizontal, cross-sectional view, taken on the line 2—2 of Figure 1,

Figure 3 is a transverse, vertical sectional view of a modified form of the invention, and

25 Figure 4 is a vertical sectional view of still another form of the invention.

In the drawing, the numeral 10 designates a nipple or short length of pipe which forms a tubular mandrel or support. The mandrel has its ends externally screw-threaded and an elastic swab cup A is mounted on said mandrel, being preferably located nearer the lower end thereof.

30 The swab cup A comprises an annular body 11 which is preferably constructed of an oil resistant material, such as "neoprene" but may be made of rubber, rubber compound or other resilient material. The body 11 has an axial bore extending therethrough and said bore is of a diameter substantially equal to the external diameter of the mandrel. The mandrel 10 passes through the

40 bore of the body and said body is preferably molded, or otherwise permanently bonded to the mandrel throughout the length of said bore, whereby the swab cup is permanently affixed to the mandrel. The upper portion of the body is provided with an integral, annular sealing lip 13

45 which has its inner surface spaced from the outer surface of the mandrel. A plurality of vertically extending ribs 14 which are integral with the lip are spaced radially around said lip (Figure 2) and 50 the inner longitudinal faces 15 of the ribs engage and are molded or bonded to the outer surface of the mandrel. Manifestly, the ribs divide the annular space between the sealing lip 13 and the mandrel into a plurality of recesses or pockets 16 55 for the reception of fluid, which will urge or dis-

tort the sealing lip radially outwardly. Since the ribs 14 are bonded to the mandrel, it is obvious that said ribs function to reinforce and brace the sealing lip 13 to limit outward radial distortion to prevent said lip from being inverted by excessive fluid pressure. The upper surface of each rib is preferably inclined as shown at 17 to facilitate upward movement of the swab cup through couplings or other irregularities (not shown) in a string of pipe or tubing B, through which the swab is moved.

For further reinforcing the sealing lip 13 to limit outward radial distortion thereof, a plurality of reinforcing, annular elements 18 are embedded within said lip. These elements may be cords, wires or the like and are molded within the lip at the time the body is formed. Manifestly, the elements aid the vertical reinforcing ribs 14 in preventing the inverting of the lip by excessive fluid pressure which enters the recesses 16 to distort the lip outwardly. If desired, the reinforcing elements may be omitted.

For strengthening and supporting the lower portion of the body, a metallic thimble or collar 19 surrounds the body and is molded or otherwise bonded thereto. The thimble encloses the entire lower portion of said body and has an opening 20 therein through which the mandrel extends. The lower portion of said thimble is rounded or curved to facilitate its passage through the tubing as it is lowered therethrough.

As has been pointed out, it is desirable to locate the swab cup at the lower portion of the mandrel, whereby the bottom of the thimble 19 is disposed adjacent the upper end of the screw threads on the lower end of said mandrel. Thus, when a coupling collar 21 is screwed onto the threads, the upper end of said collar may engage the bottom of the thimble to act as an auxiliary support and aid to some extent, in carrying the fluid load, as will be explained. Of course, the collar may be spaced from the bottom of the cup.

If desired, a plurality of swabs may be connected one above the other and as illustrated in Figure 1, a second swab assembly A1 is disposed below the swab cup A. This assembly is identical in construction to the one above described and has the upper end of its mandrel threaded into the coupling collar 21. Obviously, any required number of swabs for a predetermined load may be connected together.

The uppermost swab has the upper end of its mandrel 10 threaded into the lower end of a tubular valve cage 22 which has a plurality of fluid ports 23 in its side wall. A ball 24 is confined within the cage and is arranged to seat upon the upper end of the mandrel 10 to close the bore thereof; manifestly, when the ball is unseated an upward flow or by-pass of fluid through the mandrel is permitted. A tool joint 25 is threaded into the upper end of the valve cage and is adapted to be connected with rods 26, whereby the swab assembly may be lowered and raised within the well tubing or conductor B. Of course, a cable socket may have connection with the tool joint, in which event, the assembly may be moved through the tubing by means of a wire line or cable.

The operation of the device is obvious. The swab assembly, including one or more of the swab cups 11, is lowered downwardly through the well tubing B by means of the rods 26. When the cups 11 are in an undistorted or normal position, the outer periphery of the sealing lip 13 of each cup is spaced from the wall of the tubing, where-

by fluid within the tubing may freely by-pass the assembly as it is lowered through said fluid. A further by-pass of fluid is permitted upwardly through the tubular mandrel 10, said fluid unseating the ball valve 24 and escaping into the tubing above the swab assembly through the radial ports 23 in the valve cage 22.

When the downstroke of the assembly is complete and an upward movement is imparted to the assembly to perform the swabbing action, the ball valve 24 is automatically seated by the weight of the fluid thereupon. The fluid also enters the spaces 16 within the annular sealing lip 13 and causes an outward radial distortion of said sealing lip, whereby its outer periphery engages the wall of the well tubing B. A continued upward movement of the assembly will result in a lifting of the fluid above the assembly and obviously, since the sealing lip 13 is in sealing contact with the wall of the tubing, said wall is swabbed. The vertical reinforcing ribs 14, together with the reinforcing wires 18 which are disposed within the cups 11 acts to prevent the sealing lip 13 from being inverted by the pressure of the fluid which is lifted upon the upstroke and in this manner, an efficient swabbing action is assured.

From the above, it will be seen that a very simple and efficient swab is provided. The mandrel 10 may be a nipple or short length of pipe. The swab cup 11 is molded or otherwise permanently bonded to the outer surface of the mandrel and at the time the cup is manufactured, the reinforcing wires 18, as well as the supporting thimble 19, are molded thereto. When the swab cup becomes worn, the entire assembly, that is the cup and mandrel may be discarded and replaced with a new device. It has been found that by manufacturing the swab in the manner described, that is by permanently securing the cup directly on a short mandrel 10, the cost of the complete unit is not in excess of an ordinary swab cup which merely comprises one element of a complete swab assembly. In view of this very small cost, the unit may be discarded when worn and entirely replaced with a new unit without sacrificing economy. Since the check valve 24 seats on the upper end of the mandrel, it is obvious that each time a new assembly is substituted for a worn one, a new valve seat for said valve is provided, whereby the efficiency of the check valve is increased.

It is not always necessary to mold or bond the cup on the mandrel in order to permanently mount said cup thereon and in Figure 3, a modification of the invention is shown. In this form, the bore of the cup engages but is not attached to the surface of the mandrel, but instead, the supporting thimble 19 which encloses the lower portion of the cup and is bonded thereto, is permanently affixed to the mandrel by welding 19a, or other means. This arrangement eliminates the expense of molding or bonding the cup proper to the mandrel.

In Figure 4, a slightly modified form of the invention is shown. In this form, the supporting thimble 19 is entirely eliminated and instead of employing said thimble, the lower portion of the swab cup 11 is made of a hardened material as illustrated in Figure 4. The sealing lip 13 of this form is sufficiently flexible to be distorted radially outwardly by fluid pressure and, manifestly, the lower portion of the cup serves as a brace or reinforcement for the base of the lip 13. The function and operation of this form of

the invention is substantially the same as has been described.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A well swab including, a tubular mandrel, an elastic annular swab cup surrounding the mandrel and having the wall of its bore permanently bonded to said mandrel, a flexible sealing lip at the upper portion of the cup adapted to be distorted radially outwardly by fluid pressure and a plurality of vertical reinforcing ribs spaced radially within the sealing lip and integral with said lip, said ribs having their inner faces engaging the exterior surface of the mandrel, said inner faces being permanently bonded to the mandrel throughout their entire lengths.

2. A well swab including, a tubular mandrel, an elastic annular swab cup surrounding the mandrel and having the wall of its bore permanently bonded to said mandrel, a plurality of reinforcing ribs integral with the sealing lip and extending between said lip and the mandrel, the entire inner vertical edges or surfaces of the ribs engaging said mandrel, and means for bonding said inner surfaces of the ribs to the mandrel throughout the entire length of each of said surfaces, whereby said ribs limit outward radial movement of the lip.

3. A well swab including, a tubular mandrel, an elastic annular swab cup having a sealing lip surrounding the mandrel, a plurality of reinforcing ribs integral with the sealing lip and extending between said lip and the mandrel, said cup and ribs being bonded to the mandrel, an annular metallic thimble surrounding the lower portion of the cup below the sealing lip and molded thereto for bracing said lower portion of said cup, and means for permanently fastening the cup and thimble on the mandrel.

4. A well swab including, a tubular mandrel, an elastic annular swab cup surrounding the mandrel and having the wall of its bore permanently bonded to said mandrel, an annular flex-

ible sealing lip integral with the cup and extending upwardly therefrom, said lip having the wall of its bore spaced from the mandrel to provide an annular space between the lip and mandrel, a plurality of reinforcing ribs integral with the sealing lip and extending between said lip and the mandrel, the ribs extending throughout the vertical length of the lip and dividing the annular space between said lip and mandrel into a plurality of fluid receiving pockets, and means for bonding the inner surfaces of the ribs which engage the mandrel to the mandrel, whereby said ribs limit outward radial movement of the lip, that portion of the cup below the sealing lip being hardened, whereby such hardened portion acts to reinforce and brace the lower portion of said cup.

5. As a new article of manufacture, a swab including, a tubular support, an annular flexible swab element surrounding the support and having the lower portion of its bore engaging and permanently affixed to the support, a plurality of inwardly directed vertically extending ribs within the upper portion of the bore of the element, each rib having its inner vertical edge engaging the outer surface of the support, and means for bonding said inner edge of each rib to the support throughout the entire area of said edge.

6. A well swab including, a tubular support, an elastic annular swab cup surrounding the support and having the wall of its bore permanently bonded to said support, an annular flexible sealing lip integral with the cup and extending upwardly therefrom, said lip having the wall of its bore spaced from the support to provide an annular space between the lip and support, a plurality of reinforcing ribs integral with the sealing lip and extending between the lip and the support, the ribs extending through the vertical length of the lip and dividing the annular space between the lip and support into a plurality of fluid receiving pockets, and means for bonding the inner surfaces of the ribs which engage the support to said support, whereby said ribs limit outward radial movement of the lip.

7. A well swab as set forth in claim 6, together with means for reinforcing and bracing the lower portion of the cup below the sealing lip.

CHARLES S. CRICKMER.
